Company, Chicago, Ill., a corporation of Delaware

Application November 18, 1940, Serial No. 366,044
In Great Britain January 1, 1940

10 Claims.

(Cl. 179—5)

The present invention relates to electrical signaling systems, and has for its object the provision of a centralised indicating system enabling information to be transmitted from a distant point by a simple operation such as dialling and displayed at a suitable control point. Such a system is particularly suitable for use in air raid precautions services whereby, for example, a number of divisional control posts in an area may set up on an indicating board at a central or main control post a displayed indication of the state of the personnel thereat in the various A. R. P. services such as first aid, decontamination, and auxiliary fire brigade, that is to say, the number of persons actively engaged in each service and the number of persons in each service available for transfer to other divisions requiring them.

According to one feature of the invention, in an electrical signaling system for the transmission of information over a line in response to the operation of an impulse sender of the dial type, the initial digit is arranged to effect the selection of the appropriate group of indicating equipment which is all restored to normal on the commencement of the dialling of the succeeding digit and then operated to the appropriate setting by this and subsequent digits.

In a preferred system incorporating the invention a two-wire line, which may be an ordinary telephone line, connects the control centre to each divisional post at which is provided a telephone instrument and an impulse sending device comprising an automatic telephone dial. Each line is terminated at the control centre in impulse-responding equipment of the automatic telephone type. The control centre is also provided with an indicating board which is preferably divided vertically into a number of sections equal to the number of divisions in the area, each section being adapted to display the state of the various A. R. P. services in its corresponding division.

Assuming that provision is to be made for up to ten A. R. P. services and for a personnel of up to ninety-nine for each service in each division, a five-digit dialling scheme will be required to communicate the necessary information from a divisional post to the control centre. The first digit dialled serves to select the indicating apparatus associated with the required one of the ten A. R. P. services provided for and the succeeding four digits are received on this apparatus, the first two serving to indicate the personnel available for transfer to other divisions, while the 55

last two digits indicate the personnel already on rescue work in the calling division.

If for example in division No. 1 there are five people available for transfer and twenty-one at work in the first aid service, then the first aid service indication in column 1 of the central indicator board will be

05

21

10 If there had been twenty available and six at work, then the indication would be

20

06

Supervision is provided on the central station equipment to guard against failure to dial the full complement of digits, and in these circumstances a delayed alarm is brought into operation.

The invention will be better understood from the following description of one method of carrying it into effect, reference being had to the accompanying drawings comprising Figs. 1 and 2 which show a typical communication and signalling line between a divisional control centre and a main control centre and the circuits of the responding equipment and associated supervisory equipment required at the main control centre for each division.

The equipment shown is capable of handling up to ten A. R. P. services, although the indicating equipment for two services only is shown and it is capable of dealing with a personnel of up to ninety-nine in each of the services.

Considering now the operation, it is assumed that the divisional and main control telephones 30 DCT and MCT are of the magneto type and are connected in the line by way of transformers T₁ and T₂ respectively, the divisional control centre being provided in addition with an automatic telephone dial having the usual impulse springs IMP and shunt or off-normal springs 10. The relay E and the key K for controlling its operation which are shown dotted will be disregarded for the present.

Assuming now that the condition of service No. 1, which may be for example first aid, is to be signaled and that there are five people available for transfer and twenty-one engaged on rescue work, the five digit number to be dialled will be 10521. In response to the turning of the dial off-normal when the first digit is being dialled, the off-normal springs 10 of the dial close and complete a circuit over the two conductors of the line to operate relay AR at the main control centre. Relay AR thereupon at armature ar₁ operates relay BR and this at armature br₁

completes a circuit for the slow-to-operate relay CR. During the operating time of the latter a pulse is delivered over armature *cr1* and *br2* to the driving magnet CDM of the rotary step-by-step switch C. This switch and also the switch A are of the so-called minor type having a driving magnet which on energisation advances the wipers one step and a release magnet which on energisation restores the wipers to normal under spring control. Switch C therefore advances its wipers to position 2.

When the dial is released, its impulse springs IMP are momentarily opened once to send out one impulse and relay AR extends a pulse to the magnet ADM of rotary switch A over armature *ar1*, wiper *C1* in position 2 and armature *br6* so that wipers *A1* and *A2* are stepped to position 2. When the dial restores to normal, the off-normal springs 10 re-open and relays AR, BR and CR release in turn. A further pulse is thereupon transmitted to magnet ADM so that the wipers *A1* and *A2* are advanced a second step.

When the dial is again operated during the dialling of the second digit 0, relays AR, BR and CR operate as before and step the C switch to position 3 and during the operating time of relay CR, positive is extended over wipers *C2* and *A1* each in position 3 to energise the release magnets 19-22 of the four indicating switches associated with contact 3 on which wiper *A1* is standing. Wiper *C1* in advancing to position 3 prepares an energising circuit for the indicator driving magnet 11, negative being reconnected thereto over armature *br4* and wiper *A2* in position 3 when relay BR is energised.

It should be explained that for the purpose of indicating the state of the various services for each division, there will be provided for each of the services a set of four indicating switches of the same mechanical construction as the switches A and C, but without banks and wipers and instead pointers or indicating drums. Assuming therefore that two services are to be provided for as shown in the drawings, then an alteration to the display of service No. 1 will involve first an energisation of the release magnets 19-22, whereupon the relevant indicating switches will be restored to normal, after which a suitable train of impulses will be delivered to each of the corresponding driving magnets 11-14 in order to set up the new values. Similarly, for service No. 2, release magnets 23-26 will first be energised, after which a train of impulses will be delivered to each of the corresponding driving magnets 15-18. It will be appreciated that since the number of impulses transmitted to the driving magnets of the indicating switches will be in every case one more than the number dialled, the setting of the pointers or indicating drums will need to be adjusted accordingly.

Returning again to the operation, when the dial is released and commences to restore to normal, the train of ten impulses produced will be extended to driving magnet 11. At the end of the train, relays AR, BR and CR will be released in the usual manner and an eleventh impulse will be transmitted to magnet 11. During the operation of the dial for the next digit 5, the switch C will be stepped to position 4 so that the train of five impulses which will be produced will be extended to magnet 12 and so on.

When the full complement of digits has been dialled, the switch mechanisms associated with

the driving magnets 11, 12, 13 and 14 will have been set to display the numbers 05 21, and the control centre will thus be informed that in the first aid service for the division in question five people are available for transfer to other divisions and twenty-one people are at work therein.

Considering now the restoration of the responding equipment to normal in order that a signal corresponding to another service or another signal corresponding to the same service may be sent in from the same divisional control centre, it will be noted that on the release of relay BR with the wiper *C1* in position 6, a circuit is completed over armature *br3* for relay GR which accordingly operates. Thereupon at armature *gr1* it energises the release magnets ARM and CRM of the switches A and C so that these switches are restored to normal. The display set up on the indicator drums or the like is of course not affected.

The divisional control centre may now wish to indicate at the main control centre a change in the state of the service No. 2 or to repeat the information sent in previously in connection with this service, and this will be done by dialling a five digit number commencing with the digit 2 and followed by four further digits indicating the number of people available and working. These four digits will be effective on magnets 15, 16, 17 and 18 of the four indicating switches associated with service No. 2, the release magnets 23-26 being first operated to restore the switches to normal. Similar considerations apply to the setting of the indicating switches relating to the other services which are not shown.

It will be noted that when the switch C is advanced to position 2, relay CO is energised over wiper *C2* and thereupon locks up at armature *co1*. Relay CO also at armature *co2* prepares a delayed alarm circuit, at armature *co3* lights the supervisory lamp LP, and at armatures *co4* and *co5* opens points in the circuits of magnet TSM of the switch TS. This switch is of the well-known reverse drive step-by-step type operating always in the same direction so that no release magnet is necessary. The function of the switch is to time a suitable interval for instance twenty seconds and control the giving of an alarm if a complete number has not been dialled within this time. It will be seen that the initial operation of relay BR completes a circuit for the magnet TSM over armature *br5* and that when relay CO operates, this circuit is opened at armature *co4* whereupon the wipers *TS1*-*TS4* are advanced one step. A circuit is then completed over wiper *TS1* for the slow-to-operate relay FRA which at armature *fra1* energises the similar relay FRB and at armature *fra2* energises the magnet TSM. Relay FRB at armature *frb1* opens the circuit of relay FRA and the two relays therefore interact to step the switch TS. In normal circumstances, the complete number will have been dialled and relay GR will therefore be operated before the switch TS has stepped over the whole of its bank. Relay GR at armature *gr3* releases relay CO and the switch TS is driven to its home position in a self-interrupted circuit over wiper *TS3* or *TS4*, armature *co5* and interrupter contacts *tsm*. If the number is uncompleted however when the switch wipers have made 49 steps the driving circuit is opened by wiper *TS2* and over wiper *TS4* the alarm bell AL is operated. The switch TS remains in this position until an officer at the main control centre operates the reset key RSK which energises re-

lay GR. This relay thereupon at armature *gr1* energises the release magnets ARM and CRM of the switches A and C and at armature *gr3* releases relay CO which thereupon over armature *co5* completes the normal homing circuit for stepping the switch TS to position 1. It will be noted that at armature *gr2* relay FRB is held so as to prevent relay FRA from interfering with the homing operation. The officer will also operate the hand generator of the telephone MCT which may be individual to the calling line as shown, or may be connected thereto via a manually operated rotary switch, and thereupon rings the bell of the calling telephone DCT. The divisional control post will now be asked to repeat the codes corresponding to all the services thereat, this arrangement ensuring that the display on the indicator board is brought completely correct.

In case the divisional control centre wishes to initiate a telephone call to the main control centre, the hand generator is operated in the usual manner and ringing current is applied to the line so as to ring the bell of telephone MTC. Under these conditions relay AC, which is inoperative by direct current due to the condenser in series therewith, now operates and maintains the release magnets ARM and CRM of the switches A and C energised so as to prevent any false operation occurring due to accidental operation of relay AR by the ringing current. The condenser shunting the off-normal springs 10 serves to complete the talking circuit for telephone purposes.

In the operation of the system described it will preferably be arranged that during or after an air raid the divisional control centres will at frequent intervals signal to the main control centre the state of their A. R. P. services so that an up-to-date indication of the rescue forces available and at work in the various divisions of the area will be maintained on the main control centre indicator.

In place of the magneto type telephones it may prove more satisfactory to use common battery automatic telephones, and in this case a telephone call to the main control centre may be originated either by operating a press button which will send a distinctive signal over the line, or alternatively by dialling a distinctive first digit.

It will be appreciated that the system according to the invention is capable of dealing with a larger number of A. R. P. services and personnel for the various divisions than has been described but in this case a greater number of digits will need to be dialled to set up the required information on the central indicator board. It will also be understood that if desired the indicating switches might be provided with wipers so as to operate lamps or other indicators not suitable for direct operation.

A further modification is possible to meet the case in which the personnel for a particular service never exceeds 9. In these circumstances a single digit would always be sufficient to transmit the desired information and the dialling of two digits 0 represents waste of time and effort. It may accordingly be arranged that in response to the dialling of a first digit representing a particular service for which the above conditions obtain, a circuit is completed for automatically advancing the switch C from position 2 to a position 4 and then to position 6 so that the three digits which are dialled are operative on the

correct magnets. This may conveniently be brought about by the use of an additional wiper and bank on each of the switches A and C. The C switch wiper would be connected to negative by way of a slow relay and contacts 2 and 4 would be connected to the contact or contacts in the A switch bank corresponding to the digit or digits representing the service in question. The A switch wiper would then be connected to positive over a front contact of relay CR and a back contact of relay BR in series. The slow relay would complete a circuit for the C switch magnet. Accordingly at the end of the first digit and again at the end of the second digit, the additional relay would be energised for the slow release time of relay CR and would thus produce an extra step of the switch C. It will be understood that the indicators in the tens position with preferably be fixed and give a permanent display of the digit 0.

It may also be desirable to provide facilities whereby a divisional control post may effect immediate cancellation if the operating party thereat realises he has transmitted an incorrect digit. The error could be disposed of by finishing the dialling of the five digit number or even by dialling 1's to give a total of five digits and then at once transmitting the correct five digit number. For rendering immediate cancellation possible however use may be made of the arrangement shown dotted comprising relay E and the key K. Relay E is a differential relay having a winding in each side of the line and consequently is not affected by the normal impulse sending operation. When the key is operated, however, the lower winding only is energised and the relay then operates and at its armature *e1* energises the release magnets ARM and CRM of the A and C switches. This places the equipment in condition to have the correct number dialled immediately.

We claim:

1. In a signaling system, a calling device of the type adapted to be moved away from its normal position and to transmit impulses during its return to normal, off-normal contacts on said calling device operated whenever the movement of said calling device away from its normal position is initiated, a plurality of devices for receiving said impulses transmitted by the dial during its return to normal, and means controlled by said off-normal contacts upon each movement of said dial away from its normal position to condition a different one of said receiving devices to respond to the impulses transmitted by said calling device during its next return to normal.

2. In a signaling system, a calling device of the type adapted to be moved away from its normal position and to transmit impulses during its return to normal, an off-normal contact on said calling device operated whenever said calling device is moved away from its normal position, an automatic switch, means controlled by said off-normal contact for operating said switch once for each movement of said calling device away from its normal position, a plurality of receivers, a wiper on said switch effective to connect up a different one of said receivers upon each operation of said switch, and means for repeating over said wiper, to the receiver connected up, the impulses transmitted by said calling device during each return thereof to normal.

3. In a signaling system, a dial adapted to be moved away from its normal position and to transmit impulses during its return to normal,

off-normal contacts on said dial operated when the movement thereof away from normal is initiated, said contacts being maintained operated until the return of said dial to normal is substantially complete, an automatic switch, means controlled by each said operation of said off-normal contacts for transmitting to said switch an impulse of uniform length regardless of the length of time said contacts remain operated, thereby to operate said switch once for each movement of said dial away from its normal position, a plurality of receivers, a wiper on said switch effective to connect up a different one of said receivers upon each said operation of said switch, and means for repeating over said wiper, to the receiver connected up, the impulses transmitted by said dial during each return thereof to normal.

4. In a signaling system, a calling device of the type adapted to be moved away from its normal position and, during its return to normal, to transmit any digit in the form of a train of impulses, an off-normal contact on said calling device operated whenever said calling device is moved away from its normal position, a register having any digit registered therein, means controlled by said off-normal contact upon operating when said calling device is moved away from its normal position to restore said register to normal thereby to cancel the digit registered therein, and means then controlled by said calling device during its return to normal to register in said register the digit transmitted by said dial during such return.

5. In a signaling system, a calling device variably operable to send different digits, a plurality of registers each corresponding to a different digit, an automatic switch having access to all of said registers and controlled by said calling device in accordance with the digit sent by it on a first operation thereof to select the one of said registers which corresponds to that digit, means in the selected register controlled by said calling device, when next operated, to cancel whatever digit is already registered in said selected register, and other means in said selected register controlled by said next operation of said calling device to register therein the digit sent by said calling device upon said next operation thereof.

6. In a signaling system, a calling device variably operable to send different digits, a plurality of groups of registers, each group corresponding to a different digit, an automatic switch having access to all said groups of registers and controlled by said calling device in accordance with the digit sent by it upon a first operation thereof to select the one of said groups corresponding to that digit, means controlled by said calling device, when next operated, to restore all of the registers in the selected group to normal, thereby to cancel whatever digits are registered in said registers, means in one of the registers of the se-

lected group controlled by said next operation of said calling device to register the digit sent by said calling device upon said next operation, and means controlled by each additional operation of said calling device to register the digit sent by said calling device upon that operation in a different one of the registers of said selected group.

7. In a signaling system as claimed in claim 6, 10 a timing device, means for automatically starting said timing device to operate upon said first operation of said calling device, and means thereafter controlled by said calling device to give an alarm if said calling device is not operated 15 a predetermined number of times within a certain interval after said timing device is started.

8. In a signaling system, a plurality of indicators, a variably operable calling device, a switch having access to all of said indicators and controlled directly by said calling device, when first operated, to select any desired one of said indicators, means in the selected indicator controlled by said calling device, when next operated, to restore said indicator to normal thereby 25 to cancel the indication previously existing in said selected indicator, and other means in said selected indicator controlled by said next operation of said calling device to produce in said indicator a new indication varying in accordance 30 with the way said calling device is operated upon said next operation thereof.

9. In a signaling system, a plurality of receivers, a switch having access to all of said receivers, a calling device operated to directly control said switch to select any desired one of said receivers, a movable element in the selected receiver, at least three positions which said element may occupy, said element occupying any one of said positions at the time said receiver 40 is selected, and means thereafter controlled by another operation of said calling device for moving said element from the position occupied by it at the time said receiver is selected to any other one of said positions.

10. In a signaling system, a plurality of receivers, a switch having access to all of said receivers, a calling device operated to directly control said switch to select any desired one of said receivers, a movable element in the selected receiver, a normal position and a plurality of different off-normal positions which said element may occupy, said element occupying any one of said off-normal positions at the time said receiver is selected, and means controlled by another operation of said calling device for thereafter moving said element from the position occupied by it at the time said receiver is selected to said normal position and for then moving it from said normal position to any desired one of said off-normal positions.

JOHN HENRY RICHARD THOMAS.
WILLIE SAVILLE.
